PORTRABLE BALL PITCHING MACHINE

Carl E. Samuels, 18121 Napa St.,
Northridge, Calif. 91324

Filed Feb. 28, 1968, Ser. No. 10,768

Term of patent 14 years

(Cl. D34—5)

FIG. 2

FIGURE 1 is a reduced perspective view of the portable ball pitching machine showing my new design;

FIGURE 2 is a front elevational view thereof;

FIGURE 3 is a top plan view thereof; and

FIGURE 4 is a side elevational view thereof.

The supports are shown fragmentarily in FIGURES 2, 3 and 4 for convenience of illustration.

I claim:

The ornamental design for a portable ball pitching machine, substantially as shown and described.
